CAN COOLING APPARATUS

Bronson C. Skinner, Dunedin, Fla., assignor to
Food Machinery Corporation, San Jose, Calif.,
a corporation of Delaware

Application October 7, 1933, Serial No. 692,594

8 Claims. (Cl. 62—104)

This invention relates to improvements in can cooling apparatus and pertains to the provision of novel means for increasing the cooling efficiency of such apparatus.

5 The subject matter of the invention has to do with certain modifications and improvements in the construction of apparatus such as forms the subject matter of my co-pending application, Serial No. 654,445, now Patent No. 1,939,-
10 087, patented Dec. 12, 1933, and is particularly applicable for use in connection with cooling tanks to maintain a bath of cooling liquid at a uniform and sufficiently low temperature to quickly and efficiently cool a continuous procession of sealed, product-filled cans passing therethrough after they have been subjected to heat treatment in sterilizing or cooking apparatus.

Essentially, the object of the invention is to provide apparatus to increase the efficiency of 20 cooling tanks, and this is accomplished by removing liquid from the tank which has been heated by the entry of hot cans from a cooker or sterilizer, and by augmenting the circulation of colder liquid around the cans passing there-
25 through.

With these and other objects in view, the invention resides in the novel construction and combination of parts hereinafter described and illustrated in the accompanying drawing, in
30 which:

Figure 1 is a side elevation, partially broken away, of a cooling apparatus embodying the features of my invention.

Figure 2 is a plan view of the apparatus illustrated in Figure 1.

Figure 3 is a sectional elevation of the apparatus taken along the line 3—3 of Figure 1.

The drawing illustrates the apparatus embodying the invention as employed in connection 40 with a cooling apparatus positioned to receive sealed, product-filled cans from a cooker, both the cooker and cooler being of the type through which the cans are conveyed by means of an endless traveling conveyer, such as used for the 45 processing of products which do not require the application of temperatures above 212 degrees F. to sterilize them and which preferably should not be agitated during this process.

The cooler comprises a rectangular shaped 50 tank 1 supported by legs 2 and containing a body of cooling liquid 3, through which the cans are conveyed by means of an endless flexible conveyer 4 of any suitable construction, the one shown being of the slatted type. The cooler is
55 illustrated as being placed in end to end align-

ment with the cooker 5, end walls 6 and 7 of the cooker and cooler respectively being spaced apart a sufficient distance to prevent the absorption of heat from the one by the other. Only a portion of the cooker is illustrated, since it forms no part of the present invention.

The endless conveyer 4 extends through both the cooker and cooler and in its upper run is supported and guided by channel members 8 suitably arranged longitudinally of the cooler at 65 either side thereof. The mid-portion of the conveyer is supported by idler sprockets 9 arranged to elevate the same so that the conveyer is inclined upwardly out of the cooker and over the end walls 6 and 7 and then descends into the 70 bath of cooling liquid 3 in the cooler. At the discharge end of the cooler the conveyer 4 is inclined upwardly out of the cooler and passes over drive sprockets 10, and its return run is supported beneath the apparatus upon a series 75 of idler rollers 11.

The drive sprockets 10 are secured to a drive shaft 12 which may be driven from any suitable source of power applied to the drive pulley 13 whereby to drive the conveyer in the direction 80 indicated by the arrows.

The tank 1 is continuously supplied with cooling liquid from a supply pipe 14 located near the discharge end of the tank and provided with a plurality of discharge nozzles 15 preferably disposed 85 at an angle to the vertical, as shown, so as to assist the flow of cooling liquid along the bottom of the tank in a direction counter to the travel of the conveyer and toward the receiving end of the tank, whereby the cans are subjected to progressively cooler liquid as they pass from the receiving end of the cooler to the discharge end.

In the operation of the mechanism thus far described the hot cans are lifted out of the cooker by the inclination of the conveyer 4 over 95 the idler sprocket 9 and immersed in the bath of cooling liquid by the descent of the conveyer into the cooler. The operation of the conveyer passes the submerged cans through the cooler, their travel therethrough being timed to reduce their 100 temperature to the desired degree. The ascent of the conveyer 4 over the drive sprockets 10 at the discharge end of the cooler places the cans on the discharge table 16, from whence they may be removed as desired for labeling, storage or shipment. The cooling liquid is continuously replaced by fresh cooling liquid delivered to the tank by way of the nozzles 15, it being caused to flow through the cooler toward the receiving end 110 of the tank where, by reason of the high tempera-

ture of incoming cans, it becomes heated and rises to the surface of the tank, from whence it is removed and caused to overflow the tank by means of apparatus presently to be described.

5 As will be understood, the liquid heated by the hot cans as they pass through the cooler rises up to the surface of the liquid, and this upper stratum of heated liquid tends to circulate back toward the point of introduction of the fresh cooling 10 liquid. This flow of heated liquid towards the discharge end of the cooler, if permitted, would cause an abnormal rise in temperature of the cooling liquid towards the discharge end of the tank, resulting in decreased efficiency of the cooling 15 medium, and in order to prevent the flow of any considerable amount of this upper stratum of heated liquid toward the discharge end of the cooler I have provided means to retard the circulation of the upper stratum of heated liquid and to cause it to overflow from the tank at a point between the point of entry of the cans into the cooling liquid and their point of discharge. This is 20 accomplished by means of a trough-like baffle 17 which extends transversely across the tank at the liquid surface level and positioned with its edge 25 nearest the point of entry of incoming cans beneath the surface of the liquid. The submerged edge of the baffle 17 extends across substantially the entire width of the tank to intercept the flow 30 of the upper stratum of heated liquid as it moves toward the discharge end of the cooler and to cause it to overflow the tank through the discharge port 18 of the baffle, so that little or none 35 of the heated upper stratum of the surface liquid will pass beneath the baffle toward the discharge end of the cooler. This outlet port 18 of the baffle communicates by means of an ordinary 40 elbow pipe union with an overflow pipe 20, through which liquid overflowing from the tank 1 through the outlet 18 may be conducted to any desirable location.

However, as may readily be appreciated, product-filled cans which have been heated to temperatures approximating 212 degrees F. do not immediately give up all their heat upon contact with the cooling liquid, but as the cans pass through the cooler they continue to give up their heat to the liquid until the temperature of their contents and the temperature of the cooling liquid approaches the same degree. Also, as will be appreciated, the continued movement of the can-laden conveyer retards the flow of the currents of cooler liquid traveling along the lower portion of the tank towards the overflow end, so that the circulation of the colder liquid around the cans toward the receiving end of the tank is considerably retarded. An increasing percentage of the liquid in the tank is heated, therefore, by the continuous procession of cans, and to overcome this 45 I have made provision to draw off the upper stratum of the liquid at a second point in the rear of the baffle 17 and closer to the discharge end of the tank and deliver it to a point where it will overflow the tank by means of the baffle 17 and discharge pipe 20. This is accomplished by 50 means of additional baffles positioned throughout the length of the cooling tank as at 21 and 22, these baffles being identical in construction and operation with baffle 17 hereinbefore described. 55 The heated liquid which rises to the surface of the tank in the rear of baffle 17 is intercepted in its flow toward the point of liquid supply by the baffles 21 and 22 and caused to overflow the tank through their outlet ports 23 and 24.

75 It will be understood that the liquid skimmed

from the surface of the tank by the baffle 22 is relatively cold as compared to the liquid overflowing the tank at baffle 17, and this liquid is, therefore, returned to the tank to further assist in the cooling operation. An inclined pipe 25 80 conducts the liquid overflowing the tank at 24 to a pump 26 which forces it back into the tank 1 through the longitudinal slotted orifice 27 of the auxiliary inlet pipe 28, the latter extending transversely of the tank beneath the working run of the conveyer 4 and having its orifice 27 so positioned as to expel the liquid into the tank toward its receiving end and counter to the travel of the conveyer. 85

The baffle 21 is disposed directly above the pipe 28 and the upper stratum of liquid moving toward the discharge end of the tank is here again intercepted and caused to overflow the tank, being in turn conducted by the inclined pipe 29 to a second pump 30 and pumped into the tank 90 through the slotted orifice 31 of pipe 32, as before; the pump 30, as well as pump 26, being driven by means of power transmitted through a suitable drive shaft driven by the motor 34. 95

It is believed that it will now be apparent that 100 the flow of the cooling liquid from the nozzles 15 toward the point of entry of the cans into the tank is maintained throughout the length of the tank and repeatedly augmented as shown. Liquid flows from the surface of the tank through 105 the outlet port 24 of the baffle 22 and returns to the tank beneath the level of the conveyer 4 through the slotted orifice 27 of the pipe 28 by the pump 26. At this point the travel of the conveyer 4 and the heat given up to the liquid by 110 the cans being conveyed thereby causes the liquid to again rise to the surface of the tank, where it is intercepted by the baffle 21 and flows through the outlet port 23 and again returned to the tank beneath the level of the conveyer through the 115 orifice 31 of the pipe 32, as before; each time the liquid being returned to the tank at a point considerably in advance of the baffle by means of which it was drawn from the surface of the tank. Thus the warmer upper stratum is repeatedly 120 skimmed from the surface of the liquid and forced back into the tank beneath the conveyer until it reaches the receiving end of the tank where, having served its maximum usefulness as a cooling medium it is skimmed from the 125 surface of the tank by the baffle 17 and carried off through the discharge pipe 20.

It will be understood that the baffles and auxiliary supply pipes and their component parts disclosed and described herein are illustrative 130 only, and that various changes in their arrangement and number, as well as form, proportion, size or details of construction may be resorted to without departing from the spirit or sacrificing any of the advantages of the invention, and I 135 believe myself entitled to all such modifications as fall within the scope of the appended claims.

Having now described my invention and in what manner the same may be used, what I claim as new and desire to protect by Letters Patent is: 140

1. A can cooling apparatus comprising a tank for containing a cooling liquid, a conveyer for conveying cans through the tank beneath the surface of the liquid, means for delivering cooling liquid to said tank, a pair of baffles disposed in 145 spaced relation and extending across the width of the upper portion of the tank between the point of entry of the cans into the cooling liquid and the point of delivery of said cooling liquid to said tank, the lower portions of said baffles ex- 150

- tending below the liquid level to retard circulation of the surface stratum of said cooling liquid, a liquid outlet adjacent an end of each baffle through which moving surface liquid obstructed by said baffles may overflow from the tank, and means for receiving the overflow from the baffle nearest the discharge end of the tank and forcing the same back into the lower portion of the tank at a point in advance of said last mentioned baffle. 5
2. A can cooling apparatus comprising a tank for containing a cooling liquid, a conveyer for conveying cans through the tank beneath the surface of the liquid, means for delivering cooling liquid to said tank, a pair of baffles disposed in spaced relation across the width of the upper portion of the tank intermediate the source of liquid supply and the point of entry of the cans into the cooling liquid, said baffles being positioned with their lower portions extending below the liquid level to intercept the flow of the surface stratum of said liquid, a liquid outlet adjacent an end of each baffle through which moving surface liquid obstructed by said baffle may overflow said tank, means for receiving the liquid overflowing from the baffle nearest the discharge end of the tank and forcing the same back into the tank at a point in advance of said baffle and below the level of the conveyer, and means communicating with the outlet of the second of said baffles whereby moving surface liquid obstructed by said baffle may be discharged from the tank. 20
3. A can cooling apparatus comprising a tank for containing a cooling liquid, a conveyer for conveying cans through the tank beneath the surface of the liquid, means for delivering cooling liquid to said tank, a pair of trough-shaped baffles disposed across the upper portion of the tank between the point of liquid supply and the point of entry of the cans into the cooling liquid, a portion of each of said baffles being submerged beneath the surface of the liquid to permit the flow of the surface stratum of said liquid into said baffles, an outlet adjacent an end of the first of said baffles through which liquid flowing into said baffle may overflow the tank, means to redeliver said liquid to the lower portion of the tank at a point in advance of said baffle, means to force said liquid into said tank at said point in a direction towards the receiving end of the tank, and an outlet adjacent an end of the second of said baffles through which liquid flowing into said baffle may be discharged from the tank. 25
4. A can cooling apparatus comprising a tank for containing a cooling liquid, a conveyer for conveying cans through the tank beneath the surface of the liquid, means for delivering cooling liquid to said tank at a point near its discharge end, a baffle disposed across the width of the tank intermediate the source of liquid supply and the point of entry of the cans into the cooling liquid, said baffle being positioned with a portion thereof submerged below the liquid level to intercept the flow of the surface stratum of said liquid, a liquid outlet adjacent an end of said baffle through which moving surface liquid obstructed by said baffle may overflow said tank, means to redeliver said liquid to the tank at a point in advance of said baffle and below the level of the conveyer with sufficient force to augment the circulation of the cooling liquid, a second baffle disposed across the width of the tank at a point between the first baffle and the point of entry of the cans into the cooling liquid and positioned above the point of redelivery of the liquid from said first baffle to said tank, a liquid outlet adjacent an end of said second baffle through which moving surface liquid obstructed by said baffle may be discharged from the tank. 30
5. A can cooling apparatus comprising a tank for containing a cooling liquid, a conveyer for conveying cans through the tank beneath the surface of the liquid, means for delivering cooling liquid to said tank at a point approximating the point of discharge of the cans, means providing for the overflow of the surface stratum of liquid from the tank comprising a baffle disposed across the upper portion of the tank at a point between the source of liquid supply and the point of entry of cans into the cooling liquid, a portion of said baffle being submerged beneath the surface of the liquid to intercept the flow of said surface stratum of liquid and receive it into said baffle, means to conduct said liquid from said baffle to a point in the lower portion of said tank, means to eject said liquid into said tank, means to direct the flow of liquid being returned to said tank to augment the flow of cooling liquid therein, a second baffle disposed across the upper portion of the tank at a point between said first baffle and the point of entry of cans into the cooling liquid, a portion of said baffle being submerged to intercept the flow of surface liquid and receive it into said baffle, and means for discharging liquid received by said second baffle from the tank. 35
6. A can cooling apparatus comprising a tank for containing cooling liquid, a conveyer for conveying cans through the tank beneath the surface of the liquid, means for delivering cooling liquid to the tank at a point near its discharge end, a pair of baffles disposed in spaced relation across the width of the upper portion of the tank intermediate the source of liquid supply and the point of entry of the cans into the cooling liquid, each of said baffles having a portion thereof extending below the liquid level to intercept the flow of the surface stratum of liquid and receive it into said baffle, an outlet adjacent an end of each of said baffles to discharge the liquid received therein from the tank, and means to redeliver the liquid discharged from one of said baffles to the tank and cause it to be recirculated therethrough. 40
7. A can cooling apparatus comprising a tank for containing cooling liquid, a conveyer for conveying cans through the tank beneath the surface of the liquid, means for delivering cooling liquid to the tank at a point near its discharge end, a pair of baffles disposed in spaced relation across the width of the upper portion of the tank intermediate the source of liquid supply and the point of entry of the cans into the cooling liquid, each of said baffles having a portion thereof extending below the liquid level to intercept the flow of the surface stratum of liquid and receive it into said baffle, an outlet adjacent an end of each of said baffles to discharge liquid received therein from the tank, means to redeliver liquid discharged from one of said baffles to the tank and cause it to be recirculated therethrough comprising a pump, means to deliver liquid from said baffle to said pump, and means connecting with said pump and positioned across the lower portion of said tank through which liquid may be forced into said tank. 45
8. A can cooling apparatus comprising a tank for containing cooling liquid, a conveyer for conveying cans through the tank beneath the sur- 50

face of the liquid, means for delivering cooling liquid to the tank at a point near its discharge end, a pair of baffles disposed in spaced relation across the width of the upper portion of the tank 5 intermediate the source of liquid supply and the point of entry of the cans into the cooling liquid, each of said baffles having a portion thereof extending below the liquid level to intercept the flow of surface stratum of liquid and receive it 10 into said baffles, an outlet adjacent an end of each of said baffles to discharge liquid received therein from the tank, means to redeliver the

liquid discharged from one of said baffles to the tank and cause it to be recirculated therethrough comprising a pump, means to deliver liquid from said baffle to said pump, and an auxiliary supply pipe positioned transversely of said tank below 80 the level of the conveyer and connected with said pump through which said liquid may be redelivered to said tank, said pipe having outlet orifices therein to direct the flow of liquid being redelivered to the tank therethrough. 85
